COATING APPARATUS

George A. Miner, Medford, Mass., assignor to
United Shoe Machinery Corporation, Paterson,
N. J., a corporation of New Jersey

Application November 16, 1931, Serial No. 575,313

19 Claims. (Cl. 12—80)

My invention relates to apparatus for applying a coating to work-pieces, it being especially useful for operating upon irregular surfaces and where the area to be coated should have a sharply defined edge. In securing shoe-soles by pyroxylin or other adhesives, the preferred attaching area is upon the lasted-over margin of the upper. Although it is customary to scour this surface in preparation for the application of the coating, it remains quite rough, with irregular depressions produced by the gathered portions of the upper and frequently with projecting fastenings which attach the upper to the insole. It is highly desirable to have the coating uninterrupted over the chosen area and presenting a smooth surface to receive the outsole. It is an object of my invention to obtain this complete and uniform coating over a predetermined area.

In the attainment of this object, a feature of the invention will be found in a coating-applying member of material of such porosity that there open through its applying surface passages adapted to receive substantial quantities of the coating-substance. The material is best readily compressible, a spongy, rubber-like material such as sponge-rubber particularly well meeting the requirements. Preferably, the applying member assumes the form of a rotatable roll. Upon bringing the work into contact with a member of this character, the yield of the applying surface under the pressure of the work not only allows it to conform to the irregularities of the surface to be coated, but the adhesive in the passages of the member is forced out to enter and more or less fill the work-depressions, the entire coating being evenly spread by the rotation of the member. The roll may include an inner portion of solid rubber surrounded by an outer portion of sponge-rubber, the latter furnishing the applying surface, and being stabilized by imperforate, integral end layers. This rubber element may be compressed between opposite heads, the solid core preventing deformation of the porous portion under this pressure.

It is particularly important, in coating the lasted-over margins of shoe-uppers, that the edge of the coated area which is at the outside of the shoe-bottom shall be closely confined to a line upon the upper in proximity to the edge of the insole, this being to avoid the showing of the adhesive upon the upper after the outsole has been laid. This difficulty is overcome, as a feature of my invention, by providing a rotatable roll supplied with an adhesive and having an applying surface and at its end a chamber, said

chamber being arranged to receive an excess of the adhesive from the applying surface. As illustrated, the chamber is furnished by a series of passages opening through the periphery of the roll and by an annular passage into which the peripheral passages lead. These passages, located at the edge or edges of the roll, at which sharpness of definition of the stripes of the applied adhesive is sought, act to receive within them any excess of said adhesive which may be present, retaining it, instead of allowing it to be pressed out beyond the chosen area. I have herein shown the adhesive-receiving passages formed in one of the roll-heads, with which the previously mentioned rubber applying element may be associated.

Further features of the invention involve a scraper movable in an opening contained in a support, the scraper thus more perfectly co-operating with the surface to be cleaned, as that portion of the applying roll about the adhesive-receiving passages; and a gage member which is curved from the periphery to the end of the member and is thus effective to guide a shoe at both the end-portions and the shank in the proper relation to the applying member.

One of the several embodiments which my invention may assume is illustrated in the accompany drawing. Here

Fig. 1 is a side elevation of the more essential portions of the apparatus;

Fig. 2, a section on the line II—II of Fig. 1;

Fig. 3, a top plan view of a fragment of the machine showing the elements just below the adhesive-receptacle; and

Fig. 4, a perspective view of the applying roll, with its parts separated.

At 10 appears the end-portion of a frame-arm, upon which are carried the elements of the apparatus more closely cooperating with the work. Above the arm rises a pot or receptacle 11 for the pyroxylin or other adhesive to be employed, the flow of said adhesive being controlled by a valve 12 rotatably mounted across the delivery-opening of the receptacle. The adhesive flows through the valve into a chamber 14 opening into a casing formed between inner and outer side-plates 16 and 18, respectively, spaced from each other across a recess in the end of the arm 10 and located at the inner side of a cross-bar 20 spanning this recess and secured to the end of the frame-arm. Rotatable in the arm and extending into the casing is a power-driven shaft 22 to which is coupled at 24 an applying roll R. The side-plates and roll may be forced out-

wardly toward the bar 20, to prevent leakage of the adhesive between them, by a sleeve 26 surrounding the shaft and threaded into the arm 10. Opposite and aligned front and rear gates 28 and 30, respectively, slidable upon the tops of the side-plates, control the delivery of the adhesive from the chamber 14 to the roll R, and outer and inner scrapers 32 and 34, respectively, attached to the tops of the side-plates, clean the 10 opposite edges of the roll in a manner which will be later developed.

Considering the structure of the roll R, this has an outer disk or head 40, from which, concentric to the axis, projects an integral hub or sleeve 15 42 surrounding the end of the shaft 22 and carrying a portion of the coupling 24, which compels the shaft and roll to turn together. This hub 42 constitutes a rotatable support for the roll R. About the opposite or inner extremity of the 20 sleeve is an inner disk or head 44. The two heads may be secured to each other by screws 46 extending through openings in the outer head and threaded into the inner. Clamped between the heads is a frusto-conical roll- or body-portion 25 48 converging inwardly toward the head 44 and in direct contact at its outer end with the head 40. At its inner end, a relatively thin disk 50, provided at its periphery with work-feeding projections or teeth, is interposed between the element 30 48 and the head 44, the teeth projecting slightly outside the periphery of the former. The roll-portion 48 is of porous and readily compressible material, the best now known to me for the purpose being sponge-rubber, the passages opening 35 through the peripheral applying surface of which are of considerable diameter, say from .015 to .050 of an inch, so they will hold substantial quantities of the adhesive. It will be obvious that any spongy material of rubber-like nature 40 will be the full equivalent, for the purposes of this invention, of the sponge-rubber above mentioned. To strengthen the body portion 48 to receive the clamping force without undue distortion, it is shown as having a central section or core 52 of 45 solid rubber, and also imperforate heads or end-walls 54, 54 of rubber, which render more stable the surface which contacts with the adjacent elements. Thus, it will be seen that the imperforate layers add mechanical strength to the sponge-rubber to resist the tangential pull offered by the 50 friction between the roll and the work, and aid materially in preventing crumbling of the rubber. The imperforate layers perform also the function of keeping the spongy material and the coating material from being pushed out laterally and, thus, enable the roll to apply a stripe of coating material of unvarying width to the work, the lateral limits of this stripe being well defined. The conical rubber applying surface preferably 55 extends radially somewhat outside the periphery of the head 40, so the greater part of the surface of the element 48 may be considerably compressed by the application of the work to it. The head 44 is chambered to receive the adhesive, having formed in its inner face an annular groove 56 closed by the disk 50 to form a passage from which lead similarly closed passages 58, these, as illustrated, being first substantially 60 radial and then each having an outer inclined wall 60 terminating in a reduced outer edge 62 of the head 44. The passages 58 are shown as separated by walls 63 integral with the head. This system of passages, arranged for contact with the work along the outer edge of the stripe 65 of applied cement, permits the taking up of excess-

sive deposits of adhesive from the work. The plate 32 may be so set as to strip clean the periphery of the head 40. The plate 34 is shown as having a transverse slot 64, which receives and frictionally retains a vertical scraper blade 66 for engagement at its lower edge with the periphery of the head 44 over the passages 58. With the blade in its slot, the supporting plate 34 may be pressed into place whereupon the lower edge of the blade adjusts itself to the periphery of the head or is pressed down by the operator, being held frictionally in the slot and insuring the proper cleaning action. If desired, a like blade 67 may be carried in a longitudinal slot in the plate 32. This is most useful in guarding against 10 leakage between the roll-head 40 and the side-plate 15 18.

To aid the operator in guiding the work in contact with the roll R, a gage is provided. This gage includes a yieldable arm 68 fixed to the 20 frame-portion 10 by slot-and-screw connections 70, which enable the operator to change its angular position. This arm may be of spring-metal, and projecting from its under side, in proximity to the edge 62 of the head 44, is a member 72, 25 preferably somewhat globular, or with its periphery merging by a curve into its upper end. The side of the member 72 furnishes a contact-surface, which may be engaged by the vertically curved heel- and toe-portions of the upper of a lasted 30 shoe adjacent to the edge of the insole, to maintain it in such relation to the roll R that the shoe-bottom will be correctly guided beneath the roll to receive the adhesive over the desired area. Upon reaching the shank-portion of the shoe, the work-engaging surface of the member 72 changes, the portion of the upper projecting outwardly from the edge of the insole reaching a contact-surface at or near the end of the member. At this time, the curvature of the shank, considered vertically, 35 inclines downwardly away from the applying roll R, and the operator forces the shoe upward toward the roll to maintain its engagement therewith. Continued contact of the end of the gage member 72 with the work, without interference, 40 is permitted by the upward yield of the spring-arm 68. As the shank-portion is passed, the contact again shifts to the side of the member 72, the spring-arm returning to its normal position, and the guiding action being constantly exerted. 45 To facilitate the advance of the work over the gage, the member 72 may, if desired, be mounted to rotate on its arm. 50

In using this apparatus, the adhesive from the 55 pot 11 passes to the chamber 12 and is taken therefrom by the roll R to an amount determined by the adjustment of the gate 28. The work to be coated may consist of shoe-uppers, such as that shown at U in Fig. 2, carried by a last L and having a margin u drawn over and secured to the insole I. 60 While the gathered margin will have been treated to smooth it and generally prepare it for the reception of the adhesive, there may remain many depressions; and if metallic fastenings have been used to secure the upper, these may cause irregularities. When a surface u of this character is 65 pressed against the roll R, the gage member 72 will locate the outer edge of this margin beneath the periphery of the roll-head 44, the thin edge 62 registering with the line upon the upper determined by the edge of the insole. The periphery of the head 40 will then be substantially aligned with the inner edge of the lasted-over margin, the width of the roll being such as to give this relation. The operator presses the shoe-bottom 70 75

against the lower forward portion of the roll, and moves it rearwardly in the direction in which this contact surface of the roll is rotating, assisted in the advance by the feeding effect of the toothed disk 50, giving his chief attention to the past of the just-mentioned insole line beneath the edge 62 of the head 44. The inclination of the frusto-conical surface of the roll-portion 48, increasing in diameter inwardly of the shoe, and the yieldability of the sponge-rubber insure the necessary adhesive applying contact of the remainder of the margin u with the roll. When pockets or irregular areas upon the surface of the work reach the roll, the adhesive contained in the passages of the sponge-rubber is forced out to fill the depressions, they furnishing reservoirs which are drawn upon to provide, under all conditions, a surface of the applied adhesive which will be practically uniform. The adhesive is prevented from overrunning the chosen area at the inner side by the cleaning action of the plate 32 or its blade 67 upon the periphery of the disk 40. Here, however, the condition is not a critical one, though it is desirable to keep the insole free from the adhesive, so its flexibility shall not be reduced. At the opposite or outer side of the margin u , where overrunning will deface the upper, the periphery of the head 44 is not only cleaned by the blade 66 so it will carry no more than a thin coating of the adhesive, but, if excessive deposits by the roll-portion 48 occur, due perhaps to the very irregular surface operated upon, such bodies of adhesive, pressed out upon the periphery of the head 44, will come over the mouths of the passages 58. Into these passages the excess will enter, the inward movement away from the roll-edge 62 being facilitated by the inclination of the passage-walls 60. Once within a passage 58, the adhesive thus taken up finds the entire chamber, furnished by the annular passage 56 and the companion radial passages which are in inactive relation to the work, in which the adhesive may expand outwardly without harmful effect. In this manner, the operator continues about the entire margin u of the shoe-upper, the contact with the member 72 of the gage shifting from its side toward its bottom as an end-portion or shank-portion of the upper is operated upon.

Having described my invention, what I claim as new and desire to secure by Letters Patent of the United States is:

1. In a coating apparatus, a shaft, an applying roll removably mounted thereon and having a rigid hub, an inner portion of compressible solid rubber and an outer portion of sponge-rubber furnishing an applying surface.

2. In a shoe-coating apparatus, a disk-like sponge-rubber applying roll the width of which is small in comparison with its diameter, said roll being provided with a work-contacting coating-material-carrying body-portion, which body-portion comprises a mass of spongy material and has at each end an integral, imperforate layer strengthening said body-portion and restricting the escape of coating material laterally.

3. In a coating apparatus, an applying roll having a rigid hub, an inner portion of solid rubber and an outer portion of sponge-rubber furnishing an applying surface and having at each end an imperforate layer of rubber.

4. In a coating apparatus, a rotatable support, spaced heads carried by the support and movable toward each other, and an applying roll com-

pressed between the heads and having an inner portion of solid rubber and an outer portion of sponge-rubber furnishing an applying surface.

5. In a coating apparatus, a rotatable shaft, a sleeve surrounding the shaft and carrying a head, an opposite head movable upon the sleeve, and a body portion of sponge-rubber having integral imperforate end layers clamped between the heads thereby to form an applying roll.

6. In a coating apparatus for applying a stripe narrower than the work, means for supplying a viscous adhesive and a relatively narrow, resilient applying roll rotatable about a horizontal axis and receiving the adhesive from said supplying means and having an applying surface approximately as wide as the stripe to be applied and at its end a chamber arranged to receive an excess of the adhesive squeezed from the applying surface by the pressure of work applied to the resilient roll.

7. In a coating apparatus for applying adhesive in a stripe, adhesive-supplying means, and a rotatable applying roll receiving the adhesive therefrom and having a peripheral applying surface and at its end an annular passage communicating with the applying surface along the outer edge of the stripe.

8. In a coating apparatus, adhesive-supplying means, a relatively narrow, disk-like, resilient rotatable applying roll receiving the adhesive therefrom and having a peripheral applying surface and at its end a rigid portion provided with a series of passages opening through its periphery and a connecting passage within said passages and into which they lead.

9. In a coating apparatus, adhesive-supplying means, a rotatable, substantially cylindrical, applying roll receiving the adhesive therefrom and having a peripheral applying surface and at its end a portion provided with a series of passages opening through its periphery along the edge of the applying surface and with their outer walls inclined inwardly from a reduced peripheral edge at the end of the roll and terminating at their inner ends a connecting passage.

10. In an adhesive-applying apparatus, adhesive-supplying means, and a rotatable roll receiving the adhesive therefrom, said roll having opposite heads and an intermediate applying portion of rubber, there being in one of the heads adhesive-receiving passages opening at the periphery of the roll along the margin of the work-contacting surface.

11. In an adhesive-applying apparatus, adhesive-supplying means, and a rotatable roll receiving the adhesive therefrom, said roll having opposite heads, an intermediate applying portion of rubber and a peripherally toothed feed-disk at the inner side of one of the heads adjacent to the rubber portion.

12. In an adhesive-applying apparatus, adhesive-supplying means, and a rotatable roll receiving the adhesive therefrom, said roll having opposite heads, an intermediate applying portion of rubber, there being in one of the heads adhesive-receiving passages, and a toothed disk situated between the passages and the rubber portion.

13. In an adhesive-applying apparatus, a rotatable applying roll having opposite heads, in one of which are adhesive-receiving passages terminating at the periphery of the roll and a yieldable portion situated between the heads and with its peripheral applying surface increas-

- ing in diameter from the head with the passages toward the opposite head.
14. In an adhesive-applying apparatus, a rotatable applying roll having opposite heads, in one of which are adhesive-receiving passages, a yieldable portion situated between the heads and with its peripheral applying surface increasing in diameter from the head with the passages toward the opposite head and a toothed feed-disk 10 interposed between the end of the yieldable portion of minimum diameter and the adjacent head.
15. In a coating apparatus, a tank having a bottom outlet, a casing receiving coating material from said outlet, a rotatable applying roll in said casing, a plate interposed between the roll and the tank and provided with a slot lying transversely of the roll, and a blade movable in the slot and co-operating with the face of the roll.
16. In a coating apparatus, an adhesive receptacle, a rotatable applying roll beneath said receptacle and receiving adhesive therefrom, said applying roll having an applying surface and, at its end, a series of passages opening outwardly 25 through its periphery and an annular passage into which the peripheral passages lead, and means for controlling the passage of adhesive from the receptacle to the applying roll comprising a plate extending above the roll and provided with a slot lying transversely of the roll, said means also comprising a blade movable in the slot and cooperating with the outer ends of the 30 passages which open through the periphery.
17. In a coating apparatus, adhesive-supplying means having an outlet at the bottom, a rotatable applying roll positioned below said outlet and receiving the adhesive therefrom and having an applying surface and at its end radial passages opening into the applying surface, and a scraper co-operating with the roll at the outer ends of the passages. 5
18. In an apparatus for coating the bottoms of shoes, an adhesive-receptacle, an applying roll rotatable below the receptacle, and a spring-arm extending to a point adjacent to one side of the roll and having a globular projection with a smoothly rounded under surface depending from the under side of the arm for contact with a 15 shoe-upper.
19. In an apparatus for coating the bottoms of shoes, an adhesive receptacle, a driven applying roll rotatable below the receptacle and receiving adhesive therefrom, said applying roll being mounted upon the end of a shaft and having at its inner end a chamber arranged to receive excess adhesive from the applying surface, and a gage member associated with said inner 20 end of the roll and arranged to be engaged by the end portions of the shoe at the side of the gage member and to be engaged by the shank portion of the shoe at the end of the gage member. 25
